UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC TELEPHONE SYSTEM.

1,398,391.

Specification of Letters Patent. Patented Nov. 29, 1921.

Application filed July 28, 1919. Serial No. 313,878.

To all whom it may concern:

Be it known that I, WINFRED T. POWELL, a citizen of the United States, residing at Rochester, in the county of Monroe and 5 State of New York, have invented certain new and useful Improvements in Automatic Telephone Systems, of which the following is a full, clear, concise, and exact description.

10 This invention relates to telephone systems, and more particularly to telephone systems employing automatic switches for extending connections to various substations. It is frequently desirable in telephone systems 15 to provide call charging means either in the form of message registers or coin collecting devices for charging for the service provided. In such arrangements as soon as the called party responds, means are provided for operating the service charging device. This last named means frequently takes the form of means for reversing the current to operate the polarized magnet of the meter and when such devices are used in 20 25 a telephone system, mechanisms must be provided for disabling them whenever a call is extended for which no charge is to be made.

The present invention has for its purpose the provision of means for disabling the call 30 charging device of a subscriber's line whenever this line is extended in completing a call for which no charge is to be made.

Other features of the invention will appear from the detailed description and appended claims.

The drawing diagrammatically represents a portion of the telephone system incorporating one embodiment of the present invention. The left hand side of the drawing as 40 far as the dotted line represents a calling substation provided with a call charging device or meter, as well as the circuits of the line switch individual to this line, while the portion of the drawing between the dotted 45 lines diagrammatically represents the operating circuits of a connector switch. At the upper right hand corner of the drawing there is indicated a called station which for the purposes of this disclosure has been represented as an operator's position provided with a well known listening key, operator's head-set and signal for indicating extensions of calls to that position.

The line switch may take the form of any well known rotary switch in which the contacts connected to outgoing lines are arranged in an arcuate bank and so positioned to coöperate with brushes designed to be progressively advanced in a step-by-step manner under the control of pawl and ratchet mechanism actuated by a motor magnet. 55 The line switch herein employed has a normal position, but instead of employing a release magnet to restore this switch to its normal position when a call is abandoned, the motor magnet is actuated to advance the 60 brushes to their normal or home position. The connector switch referred to may be of a type similar to that disclosed in the patent to Keith, *et al.*, 815,176, patented 65 March 13th, 1906, when modified to operate in a so-called two-wire system. 70

The call charging device or meter is provided with a polarized magnet which is energized without effect on the initiation of a call. When, however, the called party answers the energizing effect of both windings of the magnet is cumulative to cause it to 75 operate and charge for the call.

With this brief description of the apparatus employed it is believed that the operation of the system will best be understood by describing the method of establishing a connection from a calling substation A to the 80 position of an information or trouble operator. When the calling subscriber at A removes his receiver from its switchhook, the line relay LR is energized in a circuit extending from grounded battery, resistance, line switch brush 2, inner lower back contact 80 and armature of relay 3, left hand winding of relay LR, through the substation circuits, left hand winding of the meter magnet 4, upper armature and back contact of relay 3 85 and line switch brush 5 to ground. The line relay LR attracts its armature and thereby closes a circuit from ground, conductor 6, lower winding of slow-releasing relay 7, to grounded battery. Relay 7 attracts its armatures to close an energizing circuit for 90 the relay 3, from grounded battery, lower winding of this relay, conductor 10, off normal spring and contact 8, inner-most lower armature and front contact of relay 7, conductor 6 to ground at the armature and contact of the line relay. An operating circuit 95 100 105

for the motor magnet MM is closed in multiple with the circuit just described extending from grounded battery, winding, armature and back contact of the motor magnet, 5 off normal spring and contact 8, to ground over conductor 6. Under the control of this circuit the motor magnet MM advances the brushes of the line switch from normal position into engagement with the first trunk 10 of a group of trunks terminating at the switch. If this first trunk is already seized, this condition will be indicated by the presence of ground on its terminal similar to 13, under which condition the relay 3 will be 15 maintained energized in a circuit now closed from grounded battery, lower winding of this relay, its front contact and armature, test brush 14, test terminal 13 and through a multiple test terminal and test brush similar 20 to 14, through the lower-most armature and back contact of a relay similar to 3 and through the right hand winding of a relay corresponding to line relay LR, to ground. The relay 7 is held energized in a circuit 25 traceable from grounded battery, upper winding, contact, and armature of relay 7, lower-most front contact and armature of relay 3 to ground over test brush 14 and terminal 13. The motor magnet MM is also 30 energized in a circuit completed over conductor 10, front contact and lower-most armature of relay 3, to ground over test brush 14 and terminal 13.

It will be understood that the energizing 35 circuits for relays 3 and 7 and for the motor magnet MM are successively completed at the test terminals of busy trunks. But as soon as an idle trunk is reached, the relay 3 deenergizes and thereby interrupts the operating circuits of the motor magnet MM and the energizing circuit of the slow-releasing relay 7. The relay 7, however, has a substitute holding circuit completed for itself over conductor 6 to ground at the front contact and armature of the line relay LR which is again energized as soon as a trunk is seized. Relay 3 on releasing also extends the line conductors to the connector and places a guarding potential on seized trunk. 45 As soon as the trunk whose conductors are indicated by the numerals 15 and 16 has been seized, the stepping relay SR of the connector is energized in a circuit closed from grounded battery, conductor 17, contact 18 and continuity spring, over the trunk conductor 16 and the lower side of the calling line, through the substation circuits and upper side of the calling line, trunk conductor 15, continuity spring and contact 19, 55 right hand winding of stepping relay SR, to ground. The stepping relay SR is energized in this circuit and attracts its armature to close an energizing circuit for the slow-releasing relay 20, and this relay at 60 its left hand armature opens the circuit of

the release magnet REL, and at its right hand armature and front contact closes a break point in the operating circuit of the primary motor magnet PM.

The connector is now in condition to receive the impulses corresponding to the tens digit of the wanted number, and the calling party is informed by a dial tone that he may now operate his dial or sender to transmit impulses corresponding to the wanted number. This tone is induced in a circuit extending from grounded battery, secondary winding of the induction coil, winding of the primary motor magnet PM, side switch wiper 22 in its first position, condenser 38, 75 test terminal of the selected trunk, test brush 14, lower most armature and back contact of relay 3, and right hand winding of line relay LR to ground, and is then induced in the left hand winding of the line relay LR 80 and from thence through the substation circuits of the calling line. The calling party now operates his dial in accordance with the tens digit of the wanted number causing the stepping relay SR to vibrate its armature, 85 thereby maintaining the slow-releasing relay 20 actuated, and at its back contact closes a circuit from ground, right hand front contact and armature of relay 20, winding of the slow-releasing relay 21, side switch wiper 22 in its first position, winding of the primary motor magnet PM, secondary winding of the induction coil, to grounded 90 battery. In response to the first impulse, the slow-releasing relay 21 is actuated and 100 remains actuated during this series of impulses to hold the escape magnet ESC actuated in a circuit traceable from grounded battery, resistance, winding of the escape magnet, continuity spring and armature of 105 relay 21, to ground.

At the close of the tens series of impulses, the stepping relay SR attracts its armature for a relatively long interval so that the slow-releasing relay 21 deenergizes to open 110 the circuit of the escape magnet, causing this magnet to move the side switch wipers into their second position. The calling party then operates his dial and sends a series of impulses corresponding to the units 115 digit of the wanted number. In response to this series of impulses, the stepping relay SR again vibrates its armature, but in this instance it closes an operating circuit for the secondary motor magnet SM, from 120 grounded battery, secondary winding of the induction coil, winding of the secondary magnet, lower armature and back contact of test relay TEST, also switch wiper 22 in its second position, winding of relay 21, right 125 hand armature and front contact of relay 20, back contact and armature of stepping relay SR, to ground. In response to this series of impulses, the secondary magnet SM advances the brushes 23, 24 and 25 in 130

their secondary movement to select the wanted line. At the first impulse of this series, relay 21 attracts its armature and holds it operated during the series so that the operating circuit of the escape magnet ESC previously described, is completed. At the close of the units series of impulses if the called line is idle, the escape magnet ESC deenergizes and moves the side switch 10 wipers into their third position.

If the call had been extended to a subscriber, it would have been necessary to apply ringing current to the wanted line to operate the call bell at the substation, but 15 since the call has been extended to an operator's position it is not necessary to supply the ringing current for signaling purposes. It is therefore only necessary to operate the trip magnet TRIP to move the 20 side switch wipers into their fourth position. This is accomplished in the following manner: As soon as the side switch wipers move into their third position, the escape magnet ESC is energized in a circuit traceable from grounded battery, resistance, escape magnet ESC, and side switch wiper 25 to ground. With the side switch wipers in their third position, interrupted ringing current from the ringing machine generally 30 designated 27 is supplied to the called line, but in this instance the ringing current from machine 27 operates over a circuit including the trip magnet TRIP, side switch wiper 28 in its third position, connector 35 brush 23, left hand winding of relay 29, to ground. The relay 29 is energized in this circuit, but its left hand armature 30 is slow to respond while its right hand armature is quick acting and closes a locking 40 circuit for this relay from grounded battery, its right hand winding, front contact and armature, conductor 31, test brush 25, side switch wiper 32 in its third position to ground. The trip magnet TRIP is energized in series with the left hand winding 45 of relay 29 and attracts its armature to short circuit the escape magnet. The escape magnet ESC moves the side switch wipers into the fourth or talking position. As soon 50 as the side switch wiper 32 reaches position 3 and also position 4, a circuit is closed for the lamp 33 at the operator's position, from grounded battery, armature and back contact of relay 34, conductor 31, test brush 55 25; and side switch wiper 32, to ground. The lamp 33 informs the operator that a call is awaiting attention at her position whereupon she presses the listening key LK, to connect her telephone set to the extended 60 line.

Since it is not necessary to register the call that has been extended to the operator, the meter associated with the calling line must not be operated. The magnet 4 of the 65 meter is polarized and is operated by a re-

versal of current when the called party answers. In an ordinary connection for which a charge is made, a relay similar to 35 at the connector attracts its armatures and thereby reverses the direction of the current 70 in trunk conductors 15 and 16. Since it has been assumed that the call has been extended to an operator's position, the relay 35 must not bring about this reversal of current. By reference to the diagram it will be seen 75 that in the present connection the conductor extending from the left hand winding of the relay 35 is open, whereas the right hand winding of the relay 35 is included in a circuit extending from ground to ground. 80

It will be noted by reference to the drawing that, when a trunk leading to an operator's position is selected and when the operator has thrown her listening key, the two sides 85 of this selected trunk are conductively separated by means of the condenser in series with the operator's receiver. Therefore the battery feed relay 35 of the called end of the trunk is not operated with the result that the polarized meter magnet 4 of the 90 calling line will not be actuated. Since the two sides of the trunk of the operator's position are thus conductively separated some means must be provided for tripping the ringing current. This means which has 95 been pointed out is the relay 29 which is effective to trip the ringing as soon as the operator's position has been selected. It will also be noted that as soon as the relay 29 is operated it is locked in this condition 100 over conductor 31 thus preventing the unbalancing of the conversational circuit.

Let it be assumed that the line leading to the operator's position is busy when the brushes 23, 24 and 25 were placed in operative relation to its terminals. It will be remembered that at this time the escape magnet ESC had its operating circuit closed to ground at the armature of relay 21, and when the armature of relay 21 is retracted at the close of the units series of impulses, the escape magnet ESC is maintained energized in a circuit traceable from grounded battery, resistance, winding of the escape magnet ESC, continuity spring and contact of relay 21, winding of the test relay TEST, continuity spring and contact of this relay, side switch wiper 32 in its second position, test brush 25, through the multiple test terminal of the wanted line, through a test brush similar to 25, and a side switch wiper similar to 32 in its fourth position at the connector which has previously seized the called line. The test relay TEST attracts its armatures, and 115 at its continuity spring and front contact closes a locking circuit for itself in series with the escape magnet ESC, to ground, through contact and off normal spring. At 120 the uppermost armature and front contact

125 130

of the test relay, a busy tone is applied to the calling line from the busy machine BZ.

When the calling subscriber terminates the call by replacing his receiver on the switchhook, stepping relay SR deenergizes to interrupt the operating circuit of the slow-releasing relay 20. The relay 20 retracts its armatures and closes a circuit for the release magnet REL from grounded battery, winding of this magnet, off normal spring and contact 36, back contact and armature of relay 20 to ground which releases the connector switch. The line relay LR at the line switch also retracts its armature permitting the slow-releasing relay 7 to release. This closes an operating circuit for the motor magnet MM from grounded battery, winding, armature and back contact of this magnet, off normal spring and contact 11, continuity spring and contact of relay 7 to ground. Under the control of this circuit the motor magnet MM advances the brushes of the line switch to their normal position, whereupon the off normal spring disengages the contact 11 and opens the operating circuit just described for the motor magnet.

Although no selector switches have been shown in the present disclosure, it will be readily understood that in large systems, such selectors will be interposed between the line switches and connectors as indicated at the dotted portions of conductors 15 and 16.

What I claim is:

35 1. In a telephone system, a plurality of telephone lines, a service charging device associated with certain of said lines, means for extending any one of said lines to any other line, means operative during the extension of a call from a telephone line provided with a service charging device to certain lines for operating said service charging device, and means including an electromagnetic device having elements operating in 45 different time intervals to disable said last mentioned means when no charge is to be made.

2. In a telephone system, a plurality of telephone lines, a service charging device associated with certain of said lines, means for extending any one of said lines to any other line, means operative during the extension of a call from a telephone line provided with a service charging device to certain lines for operating said service charging device, and means including a relay having fast and slow operating armatures functioning to disable said last mentioned means when no charge is to be made.

60 3. In a telephone system, a plurality of telephone lines, a service charging device associated with certain of said lines, means for extending any one of said lines to any other line, means operative during the extension of a call from a telephone line provided with a

service charging device to certain lines for operating said service charging device, and means including a relay having armatures operating in different time intervals to disable said last mentioned means. 70

4. In a telephone system, a plurality of telephone lines, a service charging device associated with certain of said lines, means for extending any one of said lines to any other line, means operative during the extension of a call from a telephone line provided with a service charging device to certain lines for operating said service charging device, and means including a relay for disabling said last mentioned means when no charge is to be made, said relay having two windings, one winding to initially energize said relay, and the other winding to maintain said relay actuated when once energized. 75 80

5. In a telephone system, telephone lines, service charging means for certain lines, operating to charge for the extension of any one of said lines to any other line, and discriminating means including an electromagnetic device having two elements operating 90 out of synchronism to determine whether or not said charging devices will be operated.

6. In a telephone system, telephone lines, service charging means for certain lines, operating to charge for the extension of any one of said lines to any other line, and a discriminating means for each of several lines, said discriminating means including an electromagnetic device having two elements operating 95 out of synchronism to determine 100 whether or not said charging devices will be operated.

7. In a telephone system, a plurality of telephone lines, means including automatic switches for interconnecting said telephone lines, a service charging device for each of certain of said lines, said device being actuated by a reversal of current, means for applying signaling current to and disconnecting same from a selected line, mechanism responsive to the completion of a call to certain of said telephone lines for reversing the current to the service charging device of the calling line to actuate the same and means including a relay having armatures 110 acting out of synchronism to disable said mechanism and to operate said signaling current disconnecting means. 115

8. In a telephone system, a plurality of telephone lines, one or more operator's lines, 120 a service charging device for each of said telephone lines arranged to be actuated by a reversal of current, mechanism for connecting signaling current to and disconnecting the same from a selected line, a device actuated by 125 the completion of a connection over a selected telephone line for operating said service charging device and actuating said mechanism and means including an electromagnetic device having elements operating out 130

of synchronism associated with each operator's line for disabling said device and for operating said mechanism.

9. In a telephone system, a plurality of 5 telephone lines, one or more operator's lines, a service charging device for each of said telephone lines arranged to be actuated by a reversal of current, a multi-position switch for connecting signaling current to and dis- 10 connecting the same from a selected tele- phone line, a device actuated by the comple- tion of a connection over a selected telephone line for operating said service charging de- 15 vice, and actuating said multi-position switch and means including an electromag- netic device having elements operating out 20 of synchronism associated with each op- erator's line for disabling said device and for operating said multi-position switch.
10. In a telephone system, a plurality of telephone lines, one or more operator's lines, a service charging device for each of said telephone lines arranged to be actuated by a reversal of current, a side switch for con- 25 necting signaling current to and disconnect- ing the same from a selected telephone line, a device actuated by the completion of a connection over a selected telephone line for operating said service charging device, and

actuating said side switch and means in- 30 cluding an electromagnetic device having elements operating out of synchronism asso- 35 ciated with each operator's line for dis- abling said device and for operating said side switch.

11. In a telephone system, a plurality of telephone lines, one or more operator's lines, a service charging device for each of said telephone lines arranged to be actuated by a reversal of current, a double wound relay 40 through which talking battery is supplied to the called end of a connection, said relay being operated on the completion of a call to a telephone line to reverse the current and to actuate the service charging device of the 45 calling telephone line, a source of signaling current and a switching device for connect- ing said source of signaling current to and disconnecting the same from a selected line and means including an electromagnetic 50 device associated with each operator's line for disabling said relay and actuating said switching device to disconnect the source of signaling current from the selected line.

In witness whereof, I hereunto subscribe 55 my name this 26th day of July, A. D. 1919.

WINFRED T. POWELL.
